[57] **CLAIM**

The ornamental design for ergonomic handle, as shown and described.

DESCRIPTION

FIG. 1 is a top, front, and right side perspective view of an ergonomic handle showing my new design;

FIG. 2 is a left side elevational view thereof; the right side elevational view being a mirror image thereof;

FIG. 3 is a front elevational view thereof;

FIG. 4 is a top plan view thereof; and,

FIG. 5 is a bottom view thereof.

The broken line showing of a door in FIGS. 1-5 is for illustrative purposes only and forms no part of the claimed design.
